UNITED STATES PATENT OFFICE.

JOHN M. STEVENSON, OF MASON CITY, IOWA.

END-GATE ROD.

1,383,168.

Specification of Letters Patent. Patented June 28, 1921.

Application filed June 22, 1920. Serial No. 390,766.

To all whom it may concern:

Be it known that I, JOHN M. STEVENSON, a citizen of the United States, residing at Mason City, in the county of Cerro Gordo 5 and State of Iowa, have invented new and useful Improvements in End-Gate Rods, of which the following is a specification.

This invention relates to means for the end gates of wagons and the principal object of the invention is to provide means whereby the end gate may be easily and firmly locked in position without using the usual screw threaded rod and nuts.

Another object of the invention is to provide an adjustable device so that the same may be used on wagons of different sizes or where the sides of the wagon have sprung.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a view showing a portion of the wagon with my invention applied thereto.

Fig. 2 is an enlarged front view of the device itself.

35 Fig. 3 is a like view showing the device in open position.

Fig. 4 is a view of the slotted bar which carries the adjustable hook.

40 Fig. 5 is a view of the adjustable hook member.

Fig. 6 is a view of the operating lever.

As shown in these drawings the device consists of the flat bar 1, the hook member 2 which is adjustably secured thereto, the

45 second flat bar 3 which carries the hook 4 which is formed therewith, and the operating lever 5. The bar 1 has the offset end 6 adjacent one end near one edge of which is the rivet hole 7. The other end of the 50 bar is provided with the roughened surface 8 and the slot 9. The hook member 2 is provided with the roughened surface 10 which engages the surface 8 and said member is secured to the bar 1 by means of the bolt 11 which passes through a hole in

said member and through the slot 9. Thus the hook member 2 is adjustably secured to the bar 1. The bar 1 is also provided with the slot 12 which is engaged by a bolt or rivet 13 passing through a hole near the 60 end of the bar 3 so that the two bars are pivotally and slidably connected at this point. An operating lever 15 is pivotally connected to the bar 1 by means of a rivet or bolt 15 carried by said lever engaging 65 the opening 7 in said bar 1 and a second rivet or bolt 16 carried by said member engaging an opening 17 which is located substantially midway the ends of the bar 3. As will be seen the parts are so arranged 70 that as the lever is tilted to a position at right-angles to the two bars the said bars will be moved into an inclined position so that the distance between the hooked ends will be shortened. I provide a combined 75 hook and finger engaging part 18 on the free end of the lever, said hook engaging the edge of the bar 3 when the device is in closed position and thus preventing further movement of the parts.

80 The hooks are formed by twisting the ends as at 19 to place the hooks parallel with the flat sides of the bars and each hook is provided with a small nib 20 at its end for engaging the thimbles carried by the 85 sides of the wagon and which receives the ends of the usual screw threaded rod for holding the tail gate in place.

It will thus be seen that after the tailgate is placed in position between the sides 90 of the wagon, as shown in Fig. 1, the nibs on the hooks are placed in engagement with the thimbles on the sides of the wagon and then the operating lever is tilted to move the hooks toward each other and thus 95 clamp the end gate between the sides of the wagon. The operating lever is of curved formation as shown so as to remain in the position in which it is set.

Attention is called to the fact that the 100 hole 7 is located adjacent one edge of the bar, while the opening 17 is located adjacent the opposite edge of the bar 3, these holes or openings receiving the rivets or bolts which connect the operating lever to 105 the bars. By this arrangement of parts with the curve in the operating lever, provides the lock. When the device is adjusted to the wagon box the position of the parts will naturally draw the operating lever 110

tighter as its pivotal points will be past center when the lever is in closed position.

It is thought from the foregoing description that the advantages and novel features 5 of my invention will be readily apparent.

I desire it to be understood that I may make changes in the construction and in the combination and arrangement of the several parts, provided that such changes 10 fall within the scope of the appended claims.

What I claim is:—

1. End gate rods of the class described comprising flat bars, hook members being carried by said bars, an operating lever, an 15 offset member provided on one of said bars adjacent one end thereof, and having a rivet hole formed near one edge of same and the remaining end of said bar having a roughened surface with a slot formed there- 20 in, one of said hook members being provided with a roughened surface which engages the roughened surface provided on said bar and said hook being adjustably secured to one of said bars, a hook engaging part pro- 25 vided on the free end of said lever, said hook engaging the edge of one of said bars

when same is in a closed position to prevent movement of parts.

2. End gate rods of the class described comprising flat bars, hook members being 30 carried by said bars, an operating lever, an offset member provided on one of said bars adjacent one end thereof, and having a rivet hole formed near one edge of same and the remaining end of said bar having a roughened surface with a slot formed therein, 35 one of said hook members being provided with a roughened surface which engages the roughened surface provided on said bar and said hook being adjustably secured on 40 one of said bars, a hook engaging part provided on the free end of said lever, said hook engaging the edge of one of said bars when same is in a closed position to prevent movement of parts, a nib being provided on each 45 of said hooks for engaging the thimbles of the wagon, said operating lever having a curved formation to provide the locking means.

In testimony whereof I affix my signature. 50

JOHN M. STEVENSON.
